ENGINE GOVERNOR

Marion Mallory, Detroit, Mich.

Application October 19, 1944, Serial No. 559,422

8 Claims. (Cl. 123—103)

This invention relates to an engine governor and more particularly to a governor for controlling the speed of an internal combustion engine.

It is the object of this invention to produce a governor which will efficiently and accurately control the speed of an internal combustion engine and which can be readily and easily adjusted to control the engine at any speed desired within a wide range of speeds.

The single figure is a view partly in section showing my governor.

The elements of my governor are as follows: intake passageway for the motive fuel 1, inlet end 2 and outlet end 3 to the engine of the intake passageway, governor valve 4 controlling fluid flow through intake passageway 1, throttle shaft 5, crank arm 6 fixed on shaft 5, spring 7 connected at one end to crank 6 and at the other end to lug 8 on the intake passageway housing, cylinder 9, piston 10, flexible or leather seals 11 on piston 10, air vent 12 to atmosphere in cylinder 9, connecting rod 13 between crank arm 6 and piston 10, conduit 14 connecting cylinder 9 into the intake passageway 1 at orifice 15 on the atmosphere side of valve 4, conduit 16 connected into the intake passageway 1 at orifice 17 on the engine side of valve 4, branch conduit 18 connecting conduit 16 into cylinder 9 and suction chamber 19, cylinder 20 communicating with conduit 16 through orifice 21, cylindrical sleeve 22 slidably adjustable within stationary cylinder 20, crank 23 fixed on screw 24 having a screw fit with the end of cylinder 20 as at 25, flange 26 on the inner end of screw 23 journaled in the right hand end of sleeve 22 as at 27, openings 28 through flange 26, slide valve 29 mounted within sleeve 22, centrifugal weights 30 pivotally connected by links 31 with ears 32 on shaft 33 driven by or in accordance with the speed of the engine or vehicle, links 34 pivotally connecting weights 30 with collar 35 which is journaled on stub shaft 36 between shoulders 37, 38, (stub shaft 36, shoulders 37, 38 and valve 29 are preferably one piece), opening 39 in the end of shaft 33 in which stub shaft 36 is journaled, pin 40 passing through slot 41 in sleeve 22, flat face 42 on valve 29 cooperating with the inner end of pin 40 to prevent turning of valve 29, atmospheric air inlet 43 in stationary cylinder 20, groove 44 communicating with orifice 43 and with orifice 45 in sleeve 22, diametrical passageway 46, axial passageway 47 in valve 29, compression spring 50.

The operation of my governor is as follows: Assuming that the engine (not shown) is running but has not reached speed sufficient to cause the

expansion of the centrifugal governor 30, 34 to move orifice 46 out of communication with opening 45 in sleeve 22, that is, the parts will be in the position shown in the drawing. At this time the suction chamber 19 will be bled to atmosphere through orifice 43, groove 44, opening 45, passageways 46, 47, orifices 28, 21, conduits 16 and 18 so that pressure in chamber 19 will be substantially atmospheric and spring 7 will hold governor valve 4 open. When the speed increases the centrifugal governor 30, 34 will move valve 29 toward the left so that passageway 46 will be offset or positioned toward the left beyond orifice 45 and valve 29 will close off orifice 45, shutting off the air bleed to suction chamber 19 and the suction or vacuum will rise (that is, the pressure will fall) in chamber 19 causing piston 10 to move toward the right and thereby moving governor valve 4 toward closed position against the tension of spring 7. This will cause the speed of the engine to fall slightly whereupon compression spring 50 will contract centrifugal weights 30 and move valve 29 to the right until passageway 46 is partially or completely in communication with orifice 45 thereby partially or completely bleeding down the vacuum in chamber 19 and permitting spring 7 to partially or completely open valve 4 to increase the charge flowing through outlet 3 into the engine.

Assume that the centrifugal governor caused valve 29 to cut off the air bleed 45 to suction chamber 19 at an engine speed of 2500 R. P. M. and it was desired to govern the engine at a higher speed. To accomplish this screw 24 would be turned inwardly or toward the left by crank 23 which would move orifice 45 toward the left and now centrifugal governor 30, 34 would have to expand a greater distance before orifice 45 would be disconnected from passageway 46 and closed to shut off the air bleed to suction chamber 19. The engine would then be governed at a higher speed. If crank 23 is turned to move sleeve 22 toward the right in the drawing, then the engine would be governed at a lower speed because centrifugal weights 30 would close orifice 45 earlier or at a lower engine speed.

As the centrifugal governor 30 moves valve 29 to the left to close air bleed orifice 45, the vacuum in valve chamber 51 to the right of valve 29 opposes the centrifugal governor 30. This vacuum exerts itself over an area equal to the area of the right hand end or face of valve 29. Thus, as centrifugal weights 30 respond to engine speed to move valve 29 to the left to close air bleed 45, the centrifugal force of the weights is opposed by

spring 50 and also by the manifold suction which is established in chamber 51 and acts upon valve 29. Thus valve 29 will only close momentarily as the engine reaches its governed speed and then will open slightly and ride the vacuum so that valve 4 will be actuated in response to load conditions and hold the engine at its governed speed. These operating conditions cause the governor system to govern the engine speed without substantial surging of the engine speed as load conditions change.

I claim:

1. A governor for an internal combustion engine having an intake passageway comprising a valve for controlling the flow of motive fluid through said passageway, a suction actuated device connected to said governor valve for imparting movement thereto, a conduit connecting said suction actuated device with the intake passageway on the engine side of said governor valve, an air bleed for said suction device, a valve controlled in accordance with engine speed for controlling said air bleed, said valve closing at a predetermined engine speed whereby said suction device moves said governor valve toward closed position, and means for adjusting the relative position of said air bleed and valve to change the speed at which the valve closes said air bleed.

2. A governor for an internal combustion engine having an intake passageway comprising a valve for controlling the flow of motive fluid through said passageway, a suction actuated device connected to said governor valve for imparting movement thereto, a conduit connecting said suction actuated device with the intake passageway on the engine side of said governor valve whereby the suction actuated device moves said governor valve toward closed position when the pressure in the intake passageway on the engine side of said governor valve is established in said suction device, an air bleed passageway leading from the suction chamber of said suction device and having an air inlet, a valve controlled in accordance with engine speed for controlling said air bleed passageway, said valve closing as the engine reaches its governed speed whereby said suction device moves the governor valve toward closed position, and means for changing the position of the air bleed inlet relative to said speed controlled valve whereby the speed at which the valve closes said air bleed is changed.

3. A governor for an internal combustion engine having an intake passageway comprising a valve for controlling the flow of motive fluid through said passageway, a suction actuated device connected to said governor valve for imparting movement thereto, a conduit connecting said suction actuated device with the intake passageway on the engine side of said governor valve whereby the suction actuated device moves said governor valve toward closed position when the suction in the intake passageway on the engine side of said governor valve is imposed upon said suction device, a valve housing having an air inlet, a conduit connecting said valve housing with the suction chamber of said suction device, a valve controlled in accordance with the engine speed and positioned in said valve housing for controlling communication between the air inlet and the said conduit, said valve closing said air inlet at a predetermined engine speed whereby said suction device moves the governor valve toward closed position, and means for adjusting the valve housing relative to the speed controlled valve to

change the engine speed at which the valve closes said air inlet.

4. A governor for an internal combustion engine having an intake passageway comprising a valve for controlling the flow of motive fluid through said passageway, a suction actuated device connected to said governor valve for imparting movement thereto, a conduit connecting said suction actuated device with the intake passageway on the engine side of said governor valve, a valve housing having an air inlet, a conduit connecting said valve housing with the suction chamber of said suction device, a valve positioned in said valve housing for controlling communication between the air inlet and the said conduit, centrifugal means controlling said valve in accordance with the engine speed, said centrifugal means actuating said valve to close said air inlet at a predetermined engine speed whereby said suction device moves the governor valve toward closed position, and means for adjusting the valve housing relative to the valve to change the engine speed at which the valve closes said air inlet.

5. A governor for an internal combustion engine having an intake passageway comprising a valve for controlling the flow of motive fluid through said passageway, a suction actuated device connected to said governor valve for imparting movement thereto, a conduit connecting said suction actuated device with the intake passageway on the engine side of said governor valve, a valve housing having an air inlet and an air outlet, a conduit connecting the said outlet with the suction chamber of said suction device, a valve controlled in accordance with the engine speed and positioned in said valve housing, said valve having a passageway therethrough whereby in one position of said valve the passageway communicates with the air inlet and air outlet for said valve housing to bleed the suction device and whereby in another position of said valve the passageway is disconnected from the air inlet to cut off the air bleed to said suction chamber, and means for adjusting the air inlet in said valve housing relative to the passageway in said speed controlled valve to change the engine speed at which the valve closes said air inlet and thereby change the governed speed of the engine.

6. A governor for an internal combustion engine having an intake passageway comprising a throttle valve for controlling the flow of motive fluid through said passageway, a suction actuated device connected to said throttle valve for imparting movement thereto, a conduit connecting said suction actuated device with the intake passageway on the engine side of the throttle valve, an air bleed orifice for said suction device, a slideable valve controlled in accordance with the engine speed for controlling said air bleed orifice, said valve sliding relative to said air bleed orifice in opposition to the intake passageway suction to close said air bleed orifice, said valve tending to close said air bleed orifice at a predetermined engine speed whereby said suction device moves said throttle valve toward closed position, and means for adjusting the relative position of said air bleed orifice and the slideable valve to change the speed at which the slideable valve closes said air bleed orifice.

7. A governor for an internal combustion engine having an intake passageway comprising a throttle valve for controlling the flow of motive fluid through said passageway, a suction actuated device connected to said throttle valve for im-

parting movement thereto, a conduit connecting said suction actuated device with the intake passageway on the engine side of said throttle valve, a cylinder having an air bleed orifice, a reciprocating valve in said cylinder for controlling said air bleed orifice, a centrifugal governor connected to said reciprocating valve for controlling the opening and closing of said valve in accordance with the engine speed, a conduit connecting the cylinder with said suction device whereby the 10 centrifugal governor moves said air bleed valve toward open position in opposition to the intake passageway suction, said centrifugal governor tending to close said air bleed valve at a predetermined engine speed whereby said suction device moves said throttle valve toward closed position, and means for adjusting the cylinder and air bleed orifice relative to said air bleed valve to change the engine speed at which the valve closes 15 said air bleed orifice.

8. A governor for an internal combustion engine having an intake passageway comprising a

5 valve for controlling the flow of motive fluid through said passageway, a suction actuated device connected to said governor valve for imparting movement thereto, a conduit connecting said suction actuated device with the intake passageway on the engine side of said governor valve, an air bleed passageway leading from the suction chamber of said suction device and having an air inlet, a valve controlled in accordance with engine speed for controlling said air bleed inlet, said air bleed valve tending to close said air inlet as the engine reaches its governed speed whereby said suction device responds to intake passageway suction and moves the governor valve toward closed position, resilient means opposing the closing of said air bleed valve, and means for adjusting the position of the air bleed inlet relative to said speed controlled valve whereby the governed speed of the engine can be changed without adjusting the stress on said resilient means.
